UNITED STATES PATENT OFFICE.

SIMON LEPESHKIN, OF STAMFORD, CONNECTICUT.

FUNNEL.

Application filed March 20, 1925. Serial No. 16,924.

- This invention relates to funnels that are used for filling narrow mouthed bottles, or receptacles generally, the invention having for an object to provide a novel and improved funnel having means applied thereto to permit of escape of air from the bottle, or other receptacle being filled while at the same time providing an adequate support for said funnel.
- 10 For further comprehension of the invention, and of the objects and advantages thereof, reference will be had to the following description and accompanying drawing, and to the appended claim in which the 15 various novel features of the invention are more particularly set forth.
- Fig. 1 of the drawing is a perspective view showing a funnel having the invention applied thereto.
- 20 Fig. 2 is a top end view thereof.
- Fig. 3 is a fragmentary vertical sectional view taken on the line 3—3 of Fig. 2.
- Fig. 4 is a top end view showing a modified construction.
- 25 Fig. 5 is a vertical sectional view taken on the line 5—5 of Fig. 4.
- Figs. 6 and 7 and 8 are top end views showing other modifications to which the device may be applied.
- 30 Referring now to the drawing, the funnel comprises a main body 10 of the usual frusto-conical form, having an aperture in the bottom thereof from which a neck or spout 11 leads downward, this neck or spout 35 being also of frusto-conical form, but of less taper than the main body of the funnel. To permit of escape of the air when the funnel is being used, a number of projections 12 are provided up the side thereof, and on the outer side of the funnel wall, which may be formed, as in Figs. 1 to 3, by channeled members 14 soldered or otherwise secured at the funnel, these members 40 preferably extending from the top of the funnel to a point about midway of the length of the spout 11, and having their lower ends beveled off as shown at 15 to better engage in a small necked bottle. When the funnel is in use the air escapes from the 45 bottle or other receptacle through passages around the projections 12, thereby enabling the filling to proceed at increased speed.
- In the form of the invention shown in Fig. 6 of the drawing the projections are 50 constituted by a number of flutes 17 formed in the side of the funnel 10^a by indenting or pressing the same inwardly at the desired points.
- In the form of the invention shown in Fig. 7, the flutes 17^a formed on the side of the funnel 10^b are pressed outwardly at the desired points.
- In the form of the invention shown in Fig. 8, the projections are provided by making the funnel 10^c of polygonal, instead of 65 circular form, preferably of octagon form as here shown.
- In the form of the invention shown in Figs. 4 and 5, the device for providing air 70 passages is in the form of a separate frusto-conical member 10^b that may be fitted on any desired funnel, such as indicated at 18, and which has a series of channeled members 14^a extending up the sides thereof to provide the air passages around the funnel 75 when placed in the neck of a bottle, or receptacle. The member 10^b does not extend downward over the spout of the funnel when in place thereon, having an opening 19 in the bottom to receive the said spout, 80 and the channeled elements 14^a have their main bodies terminating at the lower edge of the member 10^b, and are provided with extensions 20 that project downward along the sides of the spout to engage the latter. 85 These extensions 20 are arranged to be movable on the said lower ends of the members 14^a, as on hinges, so that their bottom ends will press against the spout 18^a of the funnel. To this end the said extensions are 90 connected to the main bodies of the said channeled members by means of narrow necks 21, and converge downward toward one another at such angles as may be needed to ensure of their lower ends fitting against 95 the spout of the smallest funnel to which it may be desired to apply the device, these extensions springing outward when the device is applied to a large funnel. These 100 swinging adjustments of the extensions 20 are very valuable for use when a shallow receptacle is to be filled. The receptacle being so shallow that the bottom of the spout of the funnel touches the bottom of the receptacle, while the funnel has not descended far enough for support on the mouth of the receptacle, but falls sideways. The extensions may then be adjusted outwards to form abutments to seek support 105 against the mouth of the said receptacle.
- Having thus described my invention, 110 what I claim as new and desire to protect by

Letters Patent of the United States is as follows:

The combination in a funnel attachment having a body, and a series of projections 5 extending up the side of said body on the outer face thereof to provide for air escape passages, of extensions hinged on the lower ends of the said projections, to be engaged

downward along the sides of a funnel spout, and permitting of a lateral swinging adjustment to form abutments against the mouth of a receptacle to be filled. ¹⁰

In testimony whereof I have affixed my signature.

SIMON LEPESHKIN.
